IGNITION CIRCUIT BREAKER

Marion Mallory, Detroit, Mich.

Application October 4, 1934, Serial No. 746,899

5 Claims. (Cl. 200—30)

This invention relates to ignition circuit breakers and particularly to means for eliminating sparking at the contact points. In the usual ignition circuit breaker, the breaker arm has 5 more or less freedom of movement about its pivot, so that the breaker point is free to move longitudinally and laterally a few thousandths of an inch when in operation. This slight irregularity in movement prevents perfect registration 10 of the contact points and as a result sparks are caused which oxidize the metallic surfaces of the points. Since oxidized metal is a very poor conductor of electric current, successive breaks of the electric circuit deteriorate the points at an 15 accelerated rate and the ignition system soon fails to operate at the higher speeds.

The object of the present invention is to overcome the above mentioned difficulty by means of a self-tensioning device associated with the 20 breaker arm. This device prevents any longitudinal or lateral play of the circuit breaker arm with reference to its pivot, thereby insuring more perfect registration of the contact points at all times and greatly prolonging their life.

25 The invention will be more particularly described with reference to the accompanying drawing, in which,—

Figure 1 is a plan view of a circuit breaker constructed according to the invention.

30 Figure 2 is a section taken on the line 2—2 of Figure 1.

Figure 3 is a plan view of a modified form of the invention.

Figure 4 is a section taken on the line 4—4 of 35 Figure 3.

The invention is herein illustrated in connection with a timer having two circuit breaker arms 7 mounted on pivot pins 8 within a casing 9. A spring 10 is secured in a clamp 11 and each 40 end of this spring passes about a circuit breaker arm 7 and is connected to the contact point 12 which is secured in the end 13 of the arm and cooperates with the fixed contact point 14. The spring 10 is tensioned so as to hold the contact 45 points 12, 14 closed except when they are opened by the circuit breaker cam 15 on which the lug 16 of the circuit breaker arm rides.

The circuit breaker arms 7 are so formed that 50 they pivot freely on the pins 8 and the present invention is concerned with a self-tensioning device for holding these arms so that they do not have any longitudinal or lateral play on the pins, thereby insuring positive and accurate registration of the contact points 12, 14 at all times. 55 For this purpose, a tension pin 17 is mounted

radially in the hub of each circuit breaker arm 7 and has a pointed inner end which fits in a groove 18 formed circumferentially of the pivot pin 8. The pin 17 has a close but sliding fit in the arm 7 and when the spring 10 is assembled in place, it bears against the outer end of the pin 17, so that the tapered end of the latter always fits closely in the groove 18. This has two beneficial results. It positively prevents movement 5 of the arm 7 longitudinally of the pivot pin 8 and 10 all the diametric clearance is removed between the pin 8 and the bushing 19 on the side of the breaker arm that carries the lug 16, so that the breaker arm has no play laterally of the pivot pin 8. As a result of this construction, therefore, 15 there is positive and uniform registration of the contact points at all times, their life is greatly lengthened and the quality of their performance at high speed remains perfect for a very long time.

In the modification shown in Figures 3 and 4, the breaker arm 7 is held against lateral play by a spring 20, which is secured in the clamp 11 and is tensioned to exert pressure against the end 15 of the arm. Play of the breaker arm 20 longitudinally of the pivot pin 8 is prevented by a spring 21, which is held beneath a cotter pin 22 disposed diametrically of the pivot pin. The spring 21 exerts constant downward pressure on the breaker arm 7.

It is to be understood that the specific details of the invention, as herein shown and described, are only for the purpose of illustration, and that the invention embraces all such other modifications as may fall within the scope of the appended claims.

I claim:

1. In an ignition circuit breaker, a pivot pin, a circuit breaker arm pivotally mounted thereon, a rotatable cam for rocking said arm to break the 40 circuit, a spring for rocking said arm to close the circuit, and means actuated by said spring to take up both longitudinal and lateral play of said arm with reference to said pivot pin.

2. In an ignition circuit breaker, a pivot pin, 45 a circuit breaker arm pivotally mounted thereon, said pin being formed with a circumferential groove, a tension pin mounted radially of the pivot pin bearing and having one end fitting in said groove, and spring means pressing continuously upon the other end of said tension pin.

3. In an ignition circuit breaker, a pivot pin, a circuit breaker arm pivotally mounted thereon, a rotatable cam for rocking said arm to break the 50 circuit, a spring for rocking said arm to close the circuit, a spring for rocking said arm to close 55

the circuit, said pivot pin being formed with a circumferential groove, a tension pin mounted radially of the pivot pin bearing, said spring pressing against the outer end of the tension pin and holding the inner end thereof in said groove.

4. In an ignition circuit breaker, a pivot pin, a circuit breaker arm pivotally mounted thereon, a rotatable cam for rocking said arm to break the circuit, a spring for rocking said arm to close the circuit, and a radially disposed tension pin bearing at one end against the pivot pin and at the other end against said spring to take up lateral play of the circuit breaker arm.

5. In an ignition circuit breaker, a pivot pin, a circuit breaker arm pivotally mounted thereon, a contact point on said arm, a fixed contact point cooperating therewith, a spring anchored to a fixed base with one end secured to the contact point on the arm and urging it toward the fixed contact point, and a tension pin bearing at one end against the pivot pin and at the other end against an intermediate point of the spring to take up lateral play of the circuit breaker arm. 5 10

MARION MALLORY.
